UNITED STATES PATENT OFFICE.

JAMES C. GORMAN, OF MANSFIELD, OHIO.

DUPLEX PLUNGER TRENCH PUMP.

Application filed February 8, 1926. Serial No. 86,889.

This invention relates to pumps, and more particularly to pumps known in the art as duplex plunger pumps.

The invention has for its object to provide a simple, efficient and inexpensive duplex plunger trench pump, especially designed and adapted for use in handling a large volume of muddy water, such as accumulates in excavations below the practical suction lift of 25 feet, by lifting it to say, 20 feet, by suction, and discharging it against a head of say 30 feet, if necessary.

In pumps of this character the diameter of the pump cylinder is much greater than the diameter of the suction hose, and while the velocity through the hose will be high, because of its small diameter, and will therefore carry solid material, such as sand and gravel held in suspension, the velocity through the larger diameter of the cylinder is decreased to such an extent that it is not high enough to carry the solid material on through the cylinder, and consequently it will settle down in the base of the pump under the plunger, instead of passing on through the cylinder, with the result that such material is packed and forms an obstruction that is hit by the plunger on the down stroke, thereby bending the crank shaft.

Another object is to provide a pump of the character referred to which will rid itself of the solid matter that usually settles in the base of the pump, with consequent injury to the crank shaft and other parts of the pump, as above stated.

Another object is to provide a duplex plunger pump consisting of few parts which may be easily assembled and which will afford easy access to the working parts for cleansing or repairs.

The invention will first be hereinafter more particularly described, with reference to the accompanying drawings, which are to be taken as a part of this specification, and then pointed out in the claims at the end of the description.

In said drawings, Fig. 1 is a plan view of a duplex plunger trench pump embodying my invention;

Fig. 2 is a vertical sectional elevation;

Fig. 3 is a vertical longitudinal sectional view taken at right angles to the view shown in Fig. 2; and

Fig. 4 is an inverted plan view of the

saucer-shaped attachment on the lower end of the plunger detached.

Referring to said drawings, in which the same reference letters are used to denote corresponding parts in different views, the letter A denotes the main casting or pump casing on which is mounted a crank shaft B, and a counter-shaft C which carry at one end intermeshing gears through which motion is imparted to the crank-shaft for imparting a reciprocating movement to the plungers. As shown, a pinion c on the counter-shaft engages a gear b on the crank-shaft B, and the counter-shaft is driven by gear connection with a power engine or other driving means, for imparting the desired rotary movement to the crank shaft and through it a reciprocatory movement to the plungers. Suitable bearings for the duplex crank shaft are mounted on standards A¹ on opposite sides of the main casting and an intermediate standard A², and one of the cranks at each side of said intermediate standard is connected in a well known manner with a connecting rod D which has its lower end pivotally secured to the solid bottom of a hollow plunger E, of bucket-like form, in the following manner. The connecting rod carries at its lower end a wrist-pin d which is non-rotatably secured in a bearing therefor on the bottom of the hollow plunger, said bearing consisting of a lower member having a depending exteriorly threaded boss f on its under side, which is screwed into an interiorly threaded opening 80 in the bottom of the plunger E, and having on its upper side the lower half f¹ of the wrist-pin bearing; the upper half of said bearing comprising two caps f² each having apertures in the ends thereof which register with interiorly threaded sockets in the base member f¹, and the two parts are secured together by stud bolts or screws f³ screwed into said sockets. The wrist-pin has a tri-part sleeve thereon, consisting of two outer members f⁴ having radial flanges on their inner ends and an intermediate member f⁵ fitted in the opening through the lower end of the connecting rod confined between the end flanges of the sleeve members f⁴, so as to permit oscillatory movement of the rod on the wrist-pin. The plungers E are slidably fitted within cylindrical portions of the main casting A on opposite sides thereof and are guided in their up and down movements by 105 110

means of long stuffing boxes comprising packing material G confined in annular recesses in the inner walls of the cylindrical portions of the main casting, between said walls and the outer walls of the plunger, extending approximately the full length of the points of contact between the plungers and said cylindrical portions and approximately the entire length of said cylindrical portions 10 on the inlet and discharge sides of the pump, and the packing is compressed in said recesses by means of annular rings g screwed into the upper ends of said cylindrical portions. I thus dispense with guides for the 15 plunger such as are usually employed in duplex plunger pumps as heretofore constructed. As the force of the piston stroke is exerted at the bottom of the plunger instead of the top the long packing around the plunger is the only guide necessary. The main casting A has formed therein a 20 discharge port or opening a in communication with a chamber of large capacity formed in an elbow-shaped coupling member or casting H secured to the main casting A, at one side thereof; said member H being cast in one piece with a partition and discharge chamber on each side of said partition, both arranged to discharge into a common outlet 25 pipe-connection I, for attaching a hose or the like, and upon said pipe-connection is placed an air chamber K. The discharge chambers are each provided with an outlet port 7 having a valve seat on which is seated an outwardly opening discharge valve L, preferably a rubber ball, underneath a 30 clean-out opening in the top of the casting which has a detachable cover M having depending fingers m to guide the valve to its seat. Inlet ports or openings a¹ of considerably less capacity than the discharge ports a are provided on the opposite side of the main casting A in communication with a pipe coupling N having an inlet port formed 35 with a valve seat on which is fitted an inwardly opening gravity-actuated valve L¹, preferably a rubber ball, and above said valve there is a clean-out opening on which is detachably secured a cap or cover M¹ having fingers m¹ which serve as guides for the valve and hold it in proper seating position 40 when raised by the incoming fluid. The inlet valves are in direct communication with a common suction-pipe connection P. Each plunger has rigidly secured thereto on its under side an inverted saucer-shaped device O, which has at one side an opening o, which extends from a point about its center to its circumference and its wedge-shaped form adapts it to direct any solid material, such as sand and gravel, inwardly toward the center line of the cylinder, and on the down stroke of the piston or plunger such 45 material is forcibly moved inwardly toward said center line and thence outwardly along

the open side o toward and into the discharge chamber, thus keeping the pump free from solid material and greatly facilitating the discharge of sand-laden or gravel-laden water. This device may be secured to the 70 under side or bottom of the plunger by means of set screws or other fastening means, or it may be formed as an integral part of said bottom.

A pump constructed as described will do 75 the work that has heretofore ordinarily been done by using two diaphragm pumps, as when there is a volume of water of say 10,000 gallons per hour to be handled at a head of 30 feet, the diaphragm pump which is ordinarily used will not take care of such conditions, because 30 feet is beyond the suction limit of the pump, and if a centrifugal pump of large capacity is used it will handle 80 15,000 gallons per hour and upwards, and with only a small volume to be pumped, it would quickly lose its prime, as it would pump the water faster than it flows into the excavation and therefore, where air would enter the suction line, causing it to lose its 85 prime. On the other hand, the plunger pump will pump air and water at the same time up to a suction lift of 20 feet and will, therefore, keep the water pumped down 90 without losing its prime.

My improved pump is designed to fill the gap between the diaphragm pump, which is only good for a suction lift of 25 feet, and the more expensive centrifugal pump which it is undesirable to use for the reasons 95 hereinbefore stated.

It will be observed that the discharge openings in the main casting are considerably larger than the inlet openings and open into discharge chambers of large capacity, thus giving greater freedom of movement of the liquid on the discharge side of the pump, and easy access is afforded to the suction and discharge valve by simply removing a 100 detachable cover and also to the plungers, the bottoms of which are accessible through 105 plugs P inserted in interiorly threaded openings through the bottom of the main casting.

Having thus described my invention, what I claim as new and desire to secure by Letters Patent of the United States is:—

1. In a duplex plunger pump, a main casting having cylindrical chambers on opposite sides thereof and reciprocating plungers in said chambers; each chamber being provided with a comparatively small inlet port and with a comparatively large discharge port, partitioned casing members attached to said main casting, one having a valve-controlled inlet passage and small sized openings communicating with said inlet ports and the other having at each side of its partition a discharge chamber of large capacity in communication with one of said discharge ports and leading therefrom to 115 120 125 130

a common valve-controlled outlet of comparatively small size; each of said plungers being slidably fitted in a long stuffing box extending approximately the full length of 5 the cylinder between inlet and discharge ports in said casting and approximately the entire length of the points of contact between the cylinder wall and the plunger, the packing around the plunger adapted to 10 serve as a guide therefor.

2. In a pump, a reciprocating plunger having a solid bottom pivotally secured to a connecting rod operatively connected with a crank-shaft, and means for pivotally connecting 15 said bottom with one end of said rod; said means comprising a wrist-pin fitted in an eye in the lower end of said rod and having its ends secured between upper and lower bearing members, the lower bearing member having on its under side an exteriorly threaded boss screwed into an interiorly threaded opening in said bottom, and the upper bearing member consisting of cap-pieces arranged on opposite sides of 20 the rod and having apertures therein registering with interiorly threaded sockets in said lower bearing member, and fastening bolts passing through said caps and screwed into said sockets, whereby the wrist-pin is 25 clamped between said caps and said lower bearing member so as to permit an oscillatory movement of the connecting rod.

3. In a pump having a reciprocating plunger, means for preventing sand and 30 gravel from settling in the base of the pump under the plunger, said means consisting of a device on the under side of the plunger of substantially saucer-shaped form invert-

ed and having an opening on one side thereof extending toward the discharge opening from its center to its circumference. 40

4. In a pump having a reciprocating plunger, means for preventing sand and gravel from settling in the base of the pump under the plunger, said means consisting 45 of a device of substantially saucer-shaped form inverted and having an opening on one side thereof extending toward the discharge opening from its center to its circumference; said device being detachably 50 secured to the bottom of the plunger so that it may be readily removed and replaced.

5. In a duplex plunger pump, a main casting having cylindrical chambers on opposite sides thereof and reciprocating plungers in 55 said chambers each operatively connected with a crank-shaft, each of said chambers having at one side an inlet opening of comparatively small size and at the other side a discharge opening of comparatively large 60 size, partitioned casing members attached to said main casting, one having an inlet leading to openings of small size each communicating with one of the inlet openings in said main casting and the other having a discharge chamber of large capacity on each side of its partition each communicating with one of said discharge openings and leading therefrom to a common outlet of 65 comparatively small size, a single ball-valve 70 controlling said inlet passage and a single ball-valve controlling said outlet.

In testimony whereof I affix my signature.

JAMES C. GORMAN.
